CLASP FOR GOLF BAGS

Ferdinand H. Borm, Elgin, Ill.

Application February 17, 1936, Serial No. 64,213

4 Claims. (Cl. 24—250)

This invention relates to golf bags and more especially to improved means for securing the various clubs in golf bags.

Golf bags as at present designed possess a number of important disadvantages, among which are the disorderly arrangement by which the clubs are piled or stacked in a bag such that unnecessary wear on the clubs results from rubbing together, lacings being worn through; the danger of one or more clubs slipping out of the bag and becoming lost; in addition to the fact that the club most usually desired to be withdrawn is at or near the bottom of the group, the clubs often becoming entangled. It is in order to overcome the foregoing and other objections that the present invention has been developed and perfected.

It is therefore an object of the invention to provide a simple, practical, and inexpensive device of the character described.

Another object is to provide improved golf club bag construction.

A further object is to provide a golf bag wherein the clubs are secured yet are each readily removable therefrom.

An additional object is to provide an improved golf bag wherein minimum wear on the clubs and bag will result.

Other objects and advantages will become apparent from the following specification, reference being had to the accompanying drawing, wherein:

Fig. 1 is a view partly in section of a golf bag embodying my invention;

Fig. 2 is a top sectional view taken along the line 2—2 of Fig. 1;

Fig. 3 is a partial view taken along the line 3—3 of Fig. 2, showing the detailed structure of one of the securing elements in open position and with a portion of the supporting structure removed;

Fig. 4 is a similar view to Fig. 3 but in closed position, taken along the line 4—4 of Fig. 2, showing in addition a portion of one of the club shanks secured therein;

Fig. 5 is an end view partly in section of the subject matter of Fig. 4, taken along the line 5—5 of Fig. 2; and

Fig. 6 is a separate view of one of the supporting members forming a part of the locking unit.

Referring more particularly to the drawing I show the usual golf bag 10 having an inner compartment 11, a base 12, and an open top 13. Approximately adjacent the top opening 13 a metallic ring 14 is provided and suitably secured to the top portion 13 of the bag. Disposed about the inner periphery of the ring 14 is a plurality of

club locking units designated generally by 15. Each unit consists generally of a supporting member, a latch for holding a club and a catch for securing and releasing said latch. The supporting member 16, shown separately in Fig. 6, is formed of a single piece of sheet metal cut and bent to form a T-shaped base 16, a pair of parallel flanges 17 forming with the base a U-shaped housing, and an outwardly extending lip 21 which is curved or flared at its outer end away from said housing. A rivet 18 secures one end of the base 16 to the ring 14 and the T-arms 19 are secured to the same by rivets 20. Between the flanges 17 is rotatably supported a latch member 23 as by a pivot 24, the latch members each having a circular recess 25 in an edge facing lip 21, said recess being formed between ears 26 and 27. The latch is provided with adjacent angularly disposed abutment edge 28, and 29, which latter defines one side of ear 27, for limiting the throw of the latch in open or closed positions respectively. The latch 23 is further provided with an angular recess 30 adapted to provide a shoulder 31, adjacent which is a circular edge portion 32. The U-shaped housing is further adapted to inclose and provide a mounting for a snap catch member 33 rotatably secured thereto by pivot 34. The snap catch member 33 has a recess 35 in which is located a U-shaped compression spring 36, a portion of spring 36 bearing against the base of U-shaped housing 17; and the snap catch member 33 is formed with a catch point constituting a detent 37 for engaging the shoulder 31 to hold the latch in closed position. One of the clubs 38 is shown inserted in the bag, a handle portion 39 being at the bottom of the bag, a head 40 protruding from the bag, and a shank 41 extending therein.

The operation of my device should be apparent from the foregoing description, the locking units having two normal positions as shown in Figs. 3 and 4, respectively, Fig. 3 illustrating the open or unlocked position and Fig. 4 the closed or locked position. A club is inserted in the bag in the usual manner with the handle 39 at the bottom, whereupon the shank portion 41 may be inserted in the recess 25 and pressed against abutment 27, causing the edge 29 to be swung against the base portion of member 17, the rotation of the latch member 23 causing the shoulder 31 to be swung opposite detent 37 of catch member 33, the spring 36 holding the member 33 in its closed position, resulting in shank 41 being held securely in position against the lip 21 of member 17. When it is desired to remove the club, the catch member 33 which projects a short distance beyond the

outer edges of flanges 17 can be rotated against the compression of the spring 18 manually, releasing catch point 37 from the shoulder 31 whereupon movement of the club in a direction away from the edge of the bag will swing the latch member inwardly to its open position. By this arrangement the catch 33 can be actuated by a finger or thumb of the hand grasping the club. It will thus be seen that when a number of clubs are secured in a bag in the manner described, the same are held securely against loss by accidentally dropping them from the bag and that each club will remain in its selected position, and it would be impossible for the clubs to rub against each other or against the side of the bag, thus preventing unnecessary wear which would otherwise result. Also, the desired club may be readily and quickly released and withdrawn by the use of one hand.

20 While I have shown a golf bag having four club locking units, it will be apparent that the number and arrangement are necessarily only limited by practical considerations and my invention may be utilized by having more or less than the number shown and otherwise arranged, for instance, by having some of them secured to a central supporting element within the bag.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

40 1. A clasp adapted for use in a golf bag, said clasp comprising a support consisting of a base having a pair of spaced parallel flanges, and an outwardly extending lip on said base spaced from the adjacent ends of said flanges, a latch pivotally mounted between said flanges and provided with a recess adjacent said lip for receiving the shank of a club, a spring pressed catch on the

base in cooperative relation to said latch for holding the latch in closed position, and a portion of said catch extending outwardly to be engaged by a portion of the hand grasping the club, substantially as described. 5

2. A clasp adapted for use in a golf bag, said clasp comprising a support consisting of a base having a pair of spaced parallel flanges, and an outwardly extending lip on said base spaced from the adjacent ends of said flanges, a latch pivotally mounted between said flanges and provided with a recess adjacent said lip for receiving the shank of a club, a spring pressed catch on the base in cooperative relation to said latch for holding the latch in closed position, and said latch being provided with angularly disposed abutment edges to limit its movement to open and closed positions, 10 substantially as described. 15

3. A clasp adapted for use in a golf bag, said clasp comprising a support consisting of a base 20 having a pair of spaced parallel flanges, and an outwardly extending lip on said base spaced from the adjacent ends of said flanges, a latch pivotally mounted between said flanges and provided with a recess adjacent said lip for receiving the 25 shank of a club, a shoulder formed on said latch, a spring pressed catch on the base to engage said shoulder to hold the latch in closed position, the edge of said catch extending outwardly to be engaged by a portion of the hand grasping the club, 30 whereby pressure on said extended portion will release the latch, substantially as described. 35

4. A clasp adapted for use in a golf bag, said clasp comprising a support consisting of a T-shaped base having a pair of spaced parallel 40 flanges, and an outwardly extending lip on said base spaced from the adjacent ends of said flanges, a latch pivotally mounted between said flanges and provided with a recess adjacent said lip for receiving the shank of a club, a spring 45 pressed catch on the base in cooperative relation to said latch for holding the latch in closed position, and a portion of said catch extending outwardly to be engaged by a portion of the hand grasping the club, substantially as described. 45
